GEORGE F. ROHN, OF MILWAUKEE, WISCONSIN, ASSIGNOR TO GEORGE F. ROHN ELECTRIC COMPANY, OF MILWAUKEE, WISCONSIN, A CORPORATION OF WISCONSIN.

FUSE PULLER.

1,404,324.

Specification of Letters Patent. Patented Jan. 24, 1922.

Application filed May 27, 1920. Serial No. 384,769.

To all whom it may concern:

Be it known that I, GEORGE F. ROHN, a citizen of the United States, and resident of Milwaukee, county of Milwaukee, and State 5 of Wisconsin, have invented new and useful Improvements in Fuse Pullers, of which the following is a description, reference being had to the accompanying drawings, which are a part of this specification.

10 The invention relates to a device for pulling or removing cartridge fuses from the terminals with which they are connected.

The object of the invention is to provide a 15 fuse puller which prevents or obviates any danger of the operator receiving a shock in removing or replacing the fuse, the device being readily removable from the fuse so that it may be used when desired on different fuses.

20 The invention further consists in the several features hereinafter set forth and more particularly defined by claims at the conclusion hereof.

In the drawings: Fig. 1 is a side view of 25 the device embodying the invention, parts being shown in section; Fig. 2 is a section taken on the line 2—2 of Fig. 1 with the clip shown in full and the body broken away; Fig. 3 is a section taken on the line 30 3—3 of Fig. 1; Fig. 4 is a view similar to Fig. 3 showing the device removed from the fuse.

In the drawings, the numeral 4 designates 35 a cartridge or refillable fuse of usual construction having blade contacts 5 at its ends insertable between the parts of the usual fixed terminals 6. As usually made these fuses have a cylindrical shell 7 of the fibre or other suitable insulating material and 40 metal ferrules or caps 8, the fuse link being disposed within the shell and connected to the blades. The caps 8 are of metal and connect with the blades.

In removing or replacing a fuse, if 45 through ignorance or carelessness the operator grasps the fuse so as to short circuit the current through him he will receive a shock or burn which, of course, is more dangerous the greater the voltage. To prevent 50 such an occurrence I have provided a handle 10 of insulating material which is adapted to be clamped to the fuse so that it may be readily removed therefrom. This handle extends the full length of the fuse barrel 55 and also preferably projects out over the

blades so that the operator's hand cannot come in contact with any of the metal parts of the fuse.

The handle member 10 is provided with recesses 11 receiving the upper ends of 60 clamping members 12 having clamping jaws 13. The members 12 are formed from relatively stiff metal strips and have curved ends 14 and taper to a flat base 15 provided with an opening to receive a clamping bolt 65 16 which passes upwardly through an aperture 17 in the handle and carries a clamping nut 18 which may be entirely of insulating material but is preferably provided with a threaded metal sleeve 19 and the insulated 70 exterior has a fluted beveled side 18' to permit ready turning of the nut. While these members 12 might be used alone to clamp the handle to the fuse, it is preferred to use metal clips 20 of more resilient metal in 75 conjunction therewith. Each clip 20 is formed from thin metal strips and has its ends 21 curved to surround a portion of the fuse, with its upper portion 22 shaped to conform to that of the member 12 within 80 which it is disposed, said upper portion providing a pocket 23 to receive a block 24 of insulating material in which the bolt 16 is mounted. The ends of the clip 20 project beyond the ends of the member 12 and 85 have diverging tips 25 to permit ready spreading of the clips when they are forced over the fuse.

The handle is reinforced at the points of greatest strain imposed by the clamping 90 means by means of metal plates 26 having openings 27 therein within which the clamping members are free to move.

The handle member is provided with a recessed portion 28 to permit ready circulation of air around the fuse barrel and with a sight opening 29 to permit ready inspection of the capacity indicator 30.

In Fig. 4 I have shown the position the 100 clamp is in at the time the handle is to be placed onto the fuse, the nut 18 being loosened so that the jaws 13 will pass freely over the fuse and also permit the clip 20 to be sprung over the fuse. With the parts in this position the handle is moved down onto the fuse and the nut 18 is then turned on the bolt 16 which thereby draws the member 12 and the clip 20 up into the recess 11 in the handle and in doing so causes the ends of 105 the jaws 13 to press inwardly against the 110

ends of the clip 20 to bring said clip into firm clamping engagement with the fuse so that the fuse may be readily withdrawn from the fixed terminals by grasping the handle and moving it in the proper direction.

I have shown two sets of clamping means associated with the handle but for smaller fuses a single set engaging the central portion of the fuse may be employed, particularly where the caps form the end of the fuse.

I desire it to be understood that this invention is not limited to any specific form or arrangement of parts except in so far as such limitations are specified in the claims.

What I claim as my invention is:

1. A fuse puller, comprising a handle of insulating material, means for attaching the handle to the fuse including a clip having resilient jaws engaging the cylindrical portion of the fuse, and means distinct from said jaws for pressing and maintaining them in clamping engagement with the fuse.
2. A fuse puller, comprising a handle of insulating material, a clip member carried by said handle and having resilient jaws

adapted to be pressed onto the fuse to partially surround the same, and means distinct from said jaws for securing them in engagement with the handle.

3. A fuse puller, comprising a handle of insulating material, a clip member having resilient jaws engageable with the fuse, and a clamp for said jaws carried by the handle.

4. The combination, of a handle of insulating material for a refillable fuse, a clip member engageable with the fuse, a clip clamp carried by the handle, the ends of said clip member and clip clamp being mounted within the handle, a clamping bolt connected to both members, and a clamping nut for moving the bolt to actuate the clip clamp.

5. The combination, of a handle of insulating material for a refillable fuse, having recesses therein, clip members engageable with the fuse and having portions disposed in said recesses, clip clamps having a portion disposed in said recesses, a metal reinforcement for the edges of each recess, and means for actuating the clip clamps.

In testimony whereof I affix my signature.

GEORGE F. ROHN.
